TRAVERSE ROD

Harry S. Rosenbaum, Baltimore, Md., assignor to The Eastern Venetian Blind Company, Baltimore, Md., a corporation of Maryland

Application November 8, 1956, Serial No. 621,095

8 Claims. (Cl. 211—105.2)

The present invention relates to a rod for use with curtains, drapes, and the like. More particularly, the present invention relates to a flexible rod for use in drapery or curtain installations, wherein the rod may be curved to any predetermined configuration.

This application is a continuation-in-part of my co-pending application Serial No. 484,240, filed January 26, 1955, now U.S. Patent 2,790,558, dated April 30, 1957, entitled "Traverse Rod."

Drapery and curtain rods are generally formed in one-piece constructions or include telescoping members that are movable to a desired length. Prior to the instant invention, if a curved rod was to be installed, for example, in a bay window or at the corner of a room, it was necessary to preshape the rod by using a forming jig or a tool of some kind. If a special configuration were required, it was sometimes necessary to preform the rod at the factory and only after precise measurements were taken. This procedure was not only time-consuming and uneconomical, but frequently the preformed rod did not accurately fit the installation and further adjustments were necessary to obtain the proper rod curvature. Moreover, once the heretofore known curtain or drapery rod was formed in a particular configuration to fit a specific installation, it was neither practical nor expedient to attempt to reshape the rod for another installation, if it were so desired.

It is therefore an object of the present invention to provide a curtain or drapery rod that may be formed in a desired configuration at the point of installation and without special tools.

Another object of the present invention is to provide a curtain rod that is easily bendable to effect any curved configuration desired.

Still another object of the present invention is to provide a curtain rod that is formed with a plurality of spaced laterally extending slots, the slots enabling the rod to be bent to the configuration desired.

Still another object of the present invention is to provide a curtain rod that includes laterally slotted members that are telescopically interfitted, thereby enabling the rod to be bent in any desired direction in the horizontal plane.

Still another object of the present invention is to provide a curtain rod that includes telescoping members, the inner member extending outwardly beyond the outer member for receiving additional rods and thereby defining a splicing element.

Other objects and the nature and advantages of the instant invention will be apparent from the following description taken in conjunction with the accompanying drawings, wherein:

Fig. 1 is a plan view of the curtain rod embodied in the present invention, showing the rod after it has been installed with a particular curved configuration;

Fig. 2 is an enlarged plan view of the encircled portion shown in Fig. 1, the outer member of the telescoping members being broken away;

2

Fig. 3 is a vertical sectional view taken along lines 3—3 in Fig. 2;

Fig. 4 is a plan view of the rod embodied herein located at a corner installation wherein several outer members are spliced together; and

Fig. 5 is an enlarged plan view of the encircled portion shown in Fig. 4, the outer member of the telescoping members being broken away and shown in section.

The curtain or drapery rod embodied herein may be utilized in a variety of installations and has particular application in those installations where a curved effect of the drapery or curtain is desired. The flexible rod is particularly adaptable for use in corner installations wherein a right angle bend is required and heretofore necessitated the use of separately mounted rods.

Referring now to the drawings, and particularly Figs. 1 and 2, the curtain rod embodied herein is illustrated and is indicated generally at 10. Although the rod 10 may be shaped in a variety of configurations, as shown in Fig. 1,

20 the rod is formed in a generally arcuate manner and in this form is adaptable for use in a bay window or the like. The rod 10 is flexible in construction and is adapted to be bent to any configuration necessary for a particular installation, as will hereinafter be described. Referring

25 particularly to Figs. 2 and 3, the rod 10 is shown being defined by an outer member 12 and an inner member 14 that telescopically interfits within the outer member 12. As shown in Fig. 3, the member 12 is formed in a conventional channel construction and includes a rear wall

30 16, bottom wall 18, top wall 20, and front walls 22, 24 that are joined to the top and bottom walls, respectively, and which are spaced to define an opening 26. The inner member 14 is formed in a channel construction similar to the outer member 12 and includes a rear wall 28,

35 bottom wall 30, top wall 32, and front walls 36, 34 that are joined to the top wall 32 and bottom wall 30, respectively, and which are spaced to define an opening 38. The members 12 and 14 are telescopically interfitted so that the openings 26 and 38 are in register,

40 thereby providing for access to the interior of the inner member 14. By providing for registration of the openings 26 and 38, the rod may also be used as a traverse track and as shown in Fig. 3, a roller 40 is mounted on the edge of the lower front wall 22 of the outer member

45 12 and extends interiorly of the inner member 14. Secured to the roller 40 and depending therefrom is a finger 42 that is formed with an opening at the lower end thereof for receiving a prong 44 that is fastened to a drapery indicated at 46. It is seen that the conventional drapery

50 master carriers may also be similarly mounted in the track defined by front walls 22, 24 of the outer member 12 along with other rollers and will serve to move the drapery 46 to the desired positions.

In order to render the rod 10 completely flexible in 55 construction so that it may be bent without the aid of special tools to any configuration desired, depending on the installation requirements, each of the members 12 and 14 are formed with a series of spaced transverse or laterally extending slots. Referring again to Figs. 2 and

60 3, the outer member 12 is shown being formed with spaced transverse slots 50 that extend through the rear wall 16 and through a substantial portion of the top wall 20 and bottom wall 18. By forming the outer member in this manner, the outer member may be conveniently

65 bent in a horizontal plane to any position desired, the slotted rear wall 16 and bottom and top walls providing for freedom of movement. Although the slotted outer member 12 could be utilized alone and without the aid of any stiffening element for supporting a load such as a

70 drapery, it has been found that by inserting the inner member 14 into the outer member 12, a more rigid and stable construction is provided. Since the inner member

14 must also be bendable with the outer member 12, it is formed with a series of spaced slots 52 that are oppositely positioned with respect to the slots 50 and extend from the edge of the front walls 34, 36 through a substantial portion of the bottom and top walls 30 and 32. The inner member 14 thus not only provides for rigidity of the rod construction, but enables the rod to be more effectively bent to any position desired.

As shown in Fig. 1, the inner member 14 may extend through the outer member 12 on both sides thereof and thereby constitutes the means for mounting the rod 10 on wall brackets which, in Fig. 1, are indicated at 54, 56. In this construction, the outer member 12 and inner member 14 have been bent in an arcuate shape for installation in a bay window. It is seen that the rod 10 is easily shaped without the aid of any special tools and it is furthermore seen that the spacing of the slots 50, 52 formed in the members 12, 14, respectively, provides for complete ease of forming. The double member rod 10 is not only simple to preform, but by employing the telescoping members 12 and 14, a strong and stable rod is provided. It is also seen that the inner rod provides a smooth unbroken surface that prevents the drapery drawcords from becoming frayed in the region of the bend.

In order to simplify the installation of the rod 10, it is contemplated to form the outer and inner members 12 and 14 in predetermined lengths. Thus, for any specific job, the required rod is available without the necessity of severing the ends of the outer or inner members. Normally, the inner member 14 will be cut in lengths that are somewhat longer than the outer members so that the outer ends of the inner members may project outwardly of the outer members, thereby facilitating installation. This form of the rod is shown in Fig. 1.

The installation shown in Fig. 1 is accomplished without the aid of splicing together any of the members 12 or 14. The inner member 14 extends completely through the outer member 12 and defines a one-piece channel section. Thus, the ends of the inner member extend outwardly beyond the outer member 12 and are secured to the walls 54, 56 thereby mounting the rod in position.

In certain installations, it is sometimes required to form the rod 10 at a right angle bend, such as, for example, at a corner location. The present invention is particularly adaptable for this purpose and, referring to Fig. 4, the curtain rod 10 is shown located at a corner installation, the telescoping members 12, 14 being formed in a right angle configuration to follow the outline of the wall at the corner position.

In corner and other installations where it is desirable to have the curtain or drapery cover a rather large area, the length of the rod 10 is normally insufficient to meet the length requirements of the installation. In such instances, it is necessary to extend the length of the rod and the present invention is particularly adaptable for this purpose, the use of special splicing tools or plates not being necessary or required. Normally, it is difficult to splice track sections together, since the sections must be carefully butted to provide for a smooth track over which the drapery rollers must ride. It is understood that two lengths of straight rod may be spliced together but for the purpose of illustrating the splicing arrangement embodied herein (see Figs. 4 and 5), a straight rod is shown spliced to the curved rod, the splicing structure including only the usual outer member 12 and the inner member 14 that define the rod. The splice is formed by extending the inner member 14a of the curved rod somewhat beyond the outer member 12a, the extension of the inner member 14a being indicated at 58. The straight rod to be spliced includes an outer member extension 60 that is joined to the outer member 12b which telescopically receives the inner member 14b. The extension 60 telescopically engages the extension 58 and abuts against the extreme edge 12c of the outer member 12a of the

curved rod, while the inner member extension 58 abuts against the extreme edge 14c of the inner member 14b of the straight rod. The complete rod thus formed includes the curved and straight rods, the inner members of each rod defining a smooth unbroken surface that provides for ease of cord handling which thereby prevents fraying of the cord during movement of the drapery associated therewith. The bend is simple and easy to accomplish and may be formed by hand, thereby eliminating the need for special tooling. The rod or track may be as long as desired by simply telescoping the inner and outer members of individual rod lengths. Special splicing plates are eliminated by the present invention and all size bends may be made depending on the installation requirements.

It will be obvious to those skilled in the art that various changes may be made without departing from the spirit of the invention and therefore the invention is not limited to what is shown in the drawings and described in the specification but only as indicated in the appended claims.

What is claimed is:

1. A flexible rod comprising a channel shaped inner member and a channel shaped outer member interfitting in telescoping relation, each of said members having opposed edges that define a longitudinally extending opening formed in a wall thereof, said members being positioned so that said openings register, thereby providing for access to the interior of said inner member, said outer member being formed with spaced lateral slots that extend through the back wall thereof and substantially through the top and bottom walls thereof, said inner member being formed with spaced lateral slots that extend through the front wall thereof and through a portion of the top and bottom walls thereof, said rod being bendable to any desired configuration, said slotted members providing for ease of bending said rod to the curved configuration and further providing a sufficiently rigid unit for carrying a drapery that is suspended therefrom.

2. In a curtain installation, a flexible rod including a channel shaped outer member, a channel shaped inner member located in telescoping relation in said outer member, each of said members including spaced opposed edges that define longitudinally extending slots, and spaced lateral slots formed in each of said members, said slotted members enabling said rod to be bent to a curved configuration.

3. In a curtain installation, a flexible rod including an outer member formed in a channel section having an open side, and an inner member of channel section having an open side and located in telescoping engagement in said outer member said open side being defined by spaced edges formed on said member, the open side of said channel sections being in register thereby providing for access to the interior of said inner member, said channel sections being formed with spaced lateral slots whereby said rod is bendable to a curved configuration.

4. In a curtain installation, a flexible rod including a channel shaped outer member having a series of spaced transverse slots formed therein, and a channel shaped inner member having a series of spaced transverse slots formed therein, said inner and outer members being located in telescoping relation and each of said members including spaced opposed edges that define longitudinally extending slots.

5. In a curtain installation, a plurality of rods joined together to form an elongated track, each of said rods including a channel shaped outer member formed with a series of spaced transverse slots, and a channel shaped inner member telescopically engaging said outer member and formed with a series of spaced transverse slots, said rods being spliced together by extending a portion of the inner member of one rod within a portion of the

outer member of the adjacent rod, each of said inner and outer members including spaced opposed edges that define longitudinally extending slots.

6. In a drapery installation, a traverse rod including an outer member of channel shape, said channel shaped outer member having spaced opposed edges that define a longitudinal slot therebetween, a series of spaced transversely extending slots formed in said outer member whereby said rod may be moved to a desired curved configuration, and a channel shaped insert member positioned in said outer member for adding rigidity thereto, said channel shaped insert member including spaced opposed edges that define a longitudinal slot therebetween, said second named longitudinal slot communicating with said first named longitudinal slot, and a series of spaced transverse slots formed in said insert member to provide for flexibility of movement of said traverse rod.

7. A curtain rod comprising a first elongated member of channel section having spaced opposed edges that define a longitudinal slot, spaced transverse slots formed in said member for enabling said rod to be moved to a curved position, and a second member inserted into the interior of said first member for adding rigidity thereto, said second member being of channel shape and having spaced opposed edges that define a second longitudinal slot, said second longitudinal slot communicating with the first named longitudinal slot, and spaced transverse slots formed in said second member providing for flexibility of movement of said curtain rod.

8. A curtain rod comprising an elongated outer member of channel section having spaced opposed edges that define a longitudinally extending slot formed in the front wall of said channel section, an inner elongated member of channel section telescopically interfitted in said outer member and having spaced opposed edges that define a second longitudinally extending slot formed in the front wall of said inner elongated member, said second slot communicating with the first named slot to provide access to the interior of said rod through said slots, said outer member having a plurality of spaced transversely extending slots formed therein, said inner member having a plurality of spaced transversely extending slots formed and located in opposite relation to the first named slots, 15 said transverse slots providing for flexibility of movement of said rod in a horizontal direction.
